UNITED STATES PATENT OFFICE.

HUGH MALCOLM McCORMICK, OF CHICAGO, ILLINOIS, ASSIGNOR TO UPLIFT CORSET COMPANY, OF PHOENIX, ARIZONA, A CORPORATION OF ARIZONA.

METHOD OF DESIGNING CORSET-STAYS.

1,221,811.

Specification of Letters Patent.

Patented Apr. 3, 1917.

Application filed November 4, 1914. Serial No. 870,281.

To all whom it may concern:

Be it known that I, HUGH MALCOLM McCORMICK, a citizen of the United States, residing at Chicago, in the county of Cook 5 and State of Illinois, have invented a new and useful Method of Designing Corset-Stays.

In the accompanying drawings I have illustrated one embodiment of my invention. 10 Figure 1 is an inside view of one-half of a pair of corsets over which is placed a sheet of paper upon which to take measurements for first general dimensions of intended corset stay.

15 Fig. 2 shows paper removed from half of corset with first general outline of intended corset stay drafted upon it.

Fig. 3 shows next step in drafting intended corset stay.

20 Fig. 4 shows pattern of intended corset stay, marked with grading line, cut out and divided into three sections.

In Fig. 5 the outlines of sections shown in Fig. 4 are indicated by dotted lines, and 25 solid lines show new outlines of pattern for intended corset stay.

Fig. 6 shows next step in designing pattern for intended corset stay.

Fig. 7 shows succeeding step in designing 30 pattern for intended corset stay.

Fig. 8 shows first step taken to modify final draft of lower edge of corset stay pattern.

Fig. 9 shows final step taken to modify 35 draft of lower edge of corset stay pattern.

Fig. 10 shows my design of corset stay stiffener.

Fig. 11 shows completed corset stay ready 40 to be attached to half of a pair of corsets.

Fig. 12 shows corset stay positioned upon and attached to one-half of a pair of corsets.

In "abdomen-supporting corset," Letters Patent Number 1,190,250, July 4, 1916, I show and describe a corset stay corset and 45 tell what it accomplishes.

In this specification and these drawings I show and describe how to correctly transform an ordinary corset into an intra-pelvic-abdomen-supporting, or "corset-stay," cor- 50 set.

Referring to Fig. 1: The half of corset, "XX," to be supplied with corset stay, is first fully joined, stripped, and boned, except that, at the line "W" representing the 55 line of attachment of the corset stay, the

boning is omitted for the time being and the strip "h" may either be omitted or sewed at the rear edge only, leaving the front edge unattached, until the rear edge of corset stay has been slipped under it, as hereinafter explained. This seam is located about half-way between the side of the corset and the rear edge. Upon half corset, "XX," lay a piece of ordinary tough paper "X," put thumb tacks, "Y," in positions shown, 60 through paper and corset firmly into table. The upper thumb tack should be about half an inch below the waist line, that is, at the lower edge of the zone belt. The lower thumb tack should be placed near the bottom 65 of the corset at a point, the exact location of which is explained hereinafter, said point being about two inches lower than the point TT, which latter point is a variable one, as explained later. Next draw front of corset 70 away from tacks, "Y," until same is fully stretched underneath paper "X." Now find natural waist line, "e," and measure from "e" three inches down along a line one-half inch inside the front, or clasp-edge, of corset, and 75 put in thumb tack "T." From "e" measure diagonally downward (as directed hereafter) to point, "TT." This point is approximately two inches back from the front edge of the corset. The point is located as 80 follows: Commencing at true waistline of corset, one-half inch inside front or clasp edge, measure diagonally downward nine inches to point two inches inside front edge of corset for sizes 18 to 22, inclusive; and, 85 90 similarly, in size 23, 9 $\frac{1}{4}$ inches; in size 24, 9 $\frac{1}{2}$ inches; in size 25, 9 $\frac{3}{4}$ inches; in size 26, 10 inches; in size 27, 10 $\frac{1}{4}$ inches; in size 28, 10 $\frac{1}{2}$ inches; in size 29, 10 $\frac{3}{4}$ inches; in size 30, 11 inches; in size 31, 11 $\frac{1}{4}$ inches; in size 32, 11 $\frac{1}{2}$ inches; in size 33, 11 $\frac{3}{4}$ inches; in size 34, 12 inches; in size 35, 12 $\frac{1}{4}$ inches, in size 36, 12 $\frac{1}{2}$ inches. In addition to the above dimensions, 95 allowance must be made for seams and binding. 100

Remove paper, "X," from corset and draw lines 21, 22, 23, 24, as shown in Fig. 2.

To produce Fig. 3, draw curved lines 14 and 15, obtaining lower front corner curve, "A," by placing lower end of corset stay 105 stiffener (Fig. 10) on paper slightly below meeting points of lines 23, 24; then cut out on lines 21, 14, 23, A and 15. These lines are simply smooth curves which are to be drawn approximately as shown in the drawings, al- 110

though some variation is permissible. Next draw outline of paper pattern, Fig. 3, on card-board, cut out card-board and cut into sections shown in Fig. 4.

- 5 Next place card-board sections, shown in Fig. 4, on a fresh sheet of card-board, Fig. 5, and allow width for seams by moving each section to left three-eighths of an inch on right hand side, "D," of sections 1, 2 and 3.
- 10 On right hand side of section 3 allow an additional curved segment, "F" approximately as outlined in the drawing to complement curve in corset at point where corset stay is to be joined to corset. Original outlines of sections shown in Fig. 4 are indicated in Fig. 5, by "C." At the rear edge of section 1 cut out a curved segment "E" which may vary from $\frac{1}{8}$ to more than one inch in width at the base and extend narrowing upward 20 from one-third to two-thirds of the height of said section, depending on width of goré. In Fig. 6 lay section 1 upon section 2, the upper right hand corner, "H," of section 1 about one-quarter of an inch above the upper left hand corner, "I," of section 2. Cut off lower left hand corner, "G," of section 2 even with contour, "E," of section 1. These pattern curves result in giving each corset stay a shortened lower edge upon each side 30 of the base of the abdomen, add greatly to the underreaching fit of the forward lower edge of the corset stay, and contribute to the efficiency of the lifting action, "S," Fig. 12, of the corset stay. These curves take off 35 a certain amount of each of the two sections depending on the size, as follows: sizes 18-22, $\frac{1}{8}$ inch; size 23, $\frac{3}{16}$ inch; size 24, $\frac{1}{4}$ inch; size 25, $\frac{5}{16}$ inch; size 26, $\frac{3}{8}$ inch; size 27, $\frac{7}{16}$ inch; size 28, $\frac{1}{2}$ inch; size 29, $\frac{9}{16}$ inch; size 30, 40 $\frac{5}{8}$ inch; size 31, $\frac{11}{16}$ inch; size 32, $\frac{3}{4}$ inch; size 33, $\frac{13}{16}$ inch; size 34, $\frac{5}{2}$ inch; size 35, $\frac{15}{16}$ inch; size 36, 1 inch. To provide needed room for thigh, add the triangular sections, "L," "M," Fig. 6, to the rear of section 2, and to the 45 front of section 3, about in the proportion shown, the exact amount varying in accordance with the model of corset.

Referring to Fig. 7: Lay section 2 upon section 3, the upper right hand corner, "50," 50 of section 2, about one-quarter of an inch above the left hand upper corner, "40," of section 3. The triangular shaped additions L and M having previously been made to sections 2 and 3, mark a point 32, indicating 55 the lower left hand corner.

Fig. 8 shows final draft of sections 1 and 2, incompletely cut out. Points marked "30" are punch marks to gage meeting edges of sections 1 and 2. Note that line "15" has 60 to be re-drafted for new contour of lower edge of corset stay.

Fig. 9 shows final draft of sections 1, 2 and 3, incompletely cut out, in position for final drafting of line "15." Punch marks 65 (to gage by) on meeting edges of sections 2

and 3 are indicated by "32." Line 15 is re-drafted by extending the curve representing the lower edge of the first section, whereby said curve follows the general outline of the edges of sections 2 and 3, but is rounded into a smooth curve terminating at the lower right hand corner of section 3.

The rear edge, "F," of section 3, should be extended down well below lower corner, "60," of section 1, to provide adequate anchorage to resist the secondary leverage, "S," Fig. 12, and supply a long, full curve to sufficiently and comfortably cover the thigh. The upper back corner of section 3 of corset stay should reach as high as natural waist-line of wearer. The upper front corner, "v," should be three inches below median natural waist-line 'e, and, from that point downward should recede gradually backward until the lower front corner, "60," of the corset stay is approximately two inches inside the front, or clasp-edge, of the corset. From upper back corner the corset stay should extend frontward and downward, below and obliquely away from lateral natural waist-line.

Figs. 1, 2, 3, 4, 5, 6, 7, 8, 9, and 11 show positions of, designs for and construction of corset stay for right half of pair of corsets. The same patterns reversed similarly apply to the left half of a pair of corsets.

B, shown in Figs. 4, 5, 6, 7, 8 and 9 is the grading line and is an arbitrary line drawn anywhere across the three sections shown in Fig. 5, preferably about the middle.

Referring to Figs. 11, and 12: Sections 1, 2 and 3 of corset stay are made double thickness, and their meeting edges, "n," are separately joined by seaming. Two interlinings, "a," are now stitched to outside thickness of section 1 from point "v" along front edge to point "vv" on bottom edge. The corset stay stiffener, "11," is now inserted between interlinings, "a," and pressed as far frontward and downward into corner, "60," as possible. Punch holes for eyelet, "18," and hooks, "19," are now made. Said eyelet is intended to receive a corset lacer for lacing up the front of the corset stay. Hooks, "19," are now put on by tubular rivet and stud hook machine. The inside thickness of the corset stay is now attached to corresponding outside of same by binding, "h," from upper rear corner, "9," along top, front and bottom edges to lower bottom corner, "9." Eyelet, "18," is now put in, and the completed corset stay is ready to be attached to corset. Fig. 12 shows jointure of corset stay with corset effected by overlying stripping, "k," which should have an underlying interlining immediately over raw rear edge, "F," of section 3. Said interlining is a reinforcing strip of cloth over the edge of the corset stay. Interlining and stripping, "k," are

110
115
120
125
130

sewed on simultaneously. Bone, "b," is now inserted in the usual manner.

The corset stay, combined with its lacing, should fully inclose the base and middle sections of the abdomen, approximately as high as the navel. When the ends of the corset stays are drawn toward each other by lacing, the diverged front ends exert a three-fold action upon the base of the abdomen; first, a centerward pressure away from the groins; second, an upward lift from the pelvis; third, a backward pull. This combination results in producing genuine intra-pelvic-abdominal-support. Corset stays are graded in length in accordance with the size of the corset; and, they are also graded in depth in accordance with the size of the abdomen.

The foregoing directions are intended to be used only in manufacturing different stock sizes, models and styles of corsets in quantity. It is obviously impossible to give the calculations required for what manufacturers call "specials." Any corset designer, however, understanding my invention, will be able to make his own corset stay calculations for "specials."

Corset stays operate as bent levers upon each side of the intra-pelvically situated base of the abdomen, and they are always shorter in length than the width of those portions of the corset overlying them. The initial or fulcrumic strain is indicated by arrow "R," and the secondary operation, the lift, is shown by arrow "S," Fig. 12. A pair of corset stays are obliquely positioned artificial abdominal muscles using the rear of each half of a pair of corsets as supporting bases while operating as bent levers against the right and left sides of the intra-pelvically situated abdomen.

I preferably make corset stay stiffeners, Fig. 10, of pure aluminum about 25 one-thousandths of an inch thick. They are punched, "33," for eyelets or hooks and are flexible enough to be bent by each wearer to suitably fit the contour of her abdomen. I make my corset stay stiffener of its peculiar shape that it may impinge upon the abdominal wall in such position and in such a manner as to intra-pelvically and adequately support and protect the desired region.

After combining corset stay with corset proper by stripping, "c," as hereinbefore shown and described, the corset is ready for the next usual step in manufacture.

The foregoing directions, supplemented by reference to the drawings, tell and show how to design and construct corset stays for, and combine same with, corsets ranging in sizes from 18 to 36, inclusive. The style, that is, the height of bust, length of skirt, development of either bust or hips, and the size of waist, will be found to make no dif-

ference in the resultant products, though differently shaped corset stay sections will result for each different model of corset, and the shapes and sizes of the corset-stay sections will change with increases and decreases from any size first made.

Corset manufacturers seek, in manufacturing stock, models and styles of corsets, to approximate as far as possible to the normal proportions of women of slender, medium and stout figures. In "modeling" corset stay corsets, corset designers should employ slender women, women of medium figures, and large stout women. The employment of all three types of figures will result in a degree of perfection impossible to obtain through use of a single type of figure only.

The information given and the illustrations shown of this invention are intended only for those skilled artisans of corsetry known as corset designers; and, as the physical law governing the coöperation of corset stays and corsets is distinctly different from the physical law governing the operation of corsets, *per se*, it will be necessary for corset designers, until thoroughly familiar with what I herein disclose, to pay strict attention to each detail set forth, as this art is admittedly, until mastered, difficult and recondite, involving, as it does, a radical departure from the accepted and practised arts of designing and building both corsets and abdominal supporters.

The upper front corners of corset stays may be built higher (nearer natural waist-line) if desired; I have built corset stays as high as the waist-line. Three inches below natural waist-line I have found, however, to be the best average depth for all classes of women's figures. Slight variations in depth of bottom front corners of corset stay are possible without destroying the mechanical operation of the corset stays or materially affecting the abdominal support and reduction obtained; but, only very slight variations are permissible in manufacturing corsets in quantity. As to "specials," no general dimensions can be given—each case is a law unto itself; but, if the corset designer will follow the directions described and shown herein, he will be able to provide adequate intra-pelvic abdominal support for any woman.

It has required a vast number of experiments, covering a period of more than eleven years, to invent, compare and prove the rules and processes herein set forth and to reduce same to both accuracy and simplicity. The reason so many experiments were necessary is because of the immense variety of shapes of women's figures. No part of a woman varies in size and shape to the extent of her abdomen. A school girl five feet three inches in height may wear a size 18 corset, and her mother, five feet two 130

inches in height, may wear a size 34 corset, yet both girl and woman may require intra-pelvic-abdominal support equally much. Before it was possible to set forth a dependable and definite set of rules, measurements and processes for others to follow, I had to ascertain the intra-pelvic-abdominal support and reduction requirements of a large number of differently shaped women. I have finally worked out a system of averages which can be relied upon as equally applicable everywhere. Corset manufacturers can now sell corset stay corsets with as much confidence as ordinary corsets.

15 I claim:

1. The method of designing a corset stay for corsets, constituting one of a pair of such stays, which consists in outlining on suitable material a four-sided area having the top and bottom edges converging toward the front edge, the rear edge having a height substantially equal to the distance from the waist line to the lower part of the corset, the length of said area being slightly less than the distance from a line between the side and the rear edge of the corset, to the front edge thereof, dividing said area into a plurality of sections on lines running from the top to the bottom, curving certain of the vertical edges thereof and providing the bottom of the combined areas with a concave edge.

2. The method of constructing corset stays for corsets, which consists in prepar-

ing a four-sided sheet having one edge substantially equal to the distance from the waist line of the corset to the bottom thereof and having top and bottom edges converging toward the front edge, the length of said sheet being less than the distance from a line between the side and the rear edge of the corset, to the front edge thereof, curving inwardly the top and bottom of said sheet, dividing said sheet into three sections on lines substantially parallel to the front and rear edges thereof, reproducing said sections on another sheet but enlarged to allow for seams, goring the adjacent lower corners of the front and middle sections to produce a convexity of the adjacent areas, rounding the outside of the rear section to allow for the curve in the corset, increasing the middle and rear sections in width from the top diagonally downwardly along their adjacent edges, to partially offset the decrease in the length of the lower edge caused by cutting out said gores, arranging said three sections side by side in contact at the bottom, and continuing the curve of the first section along the base of the other two sections to produce a smooth curve to the extreme opposite corner, substantially as illustrated.

HUGH MALCOLM McCORMICK.
